UNITED STATES PATENT OFFICE.

EDWARD J. LA FONTAINE, OF MINNEAPOLIS, MINNESOTA.

REFRIGERATOR COUNTER.

Application filed December 26, 1923. Serial No. 682,786.

My invention provides certain highly important improvements in the construction of refrigerator counters, and, generally stated, the invention consists of the novel construction, combinations and arrangement of parts hereinafter described and defined in the claims.

The type of counter herein designated as a refrigerator counter is one in which the compartment for containing and displaying meat, vegetables and other perishable articles of food is covered with a glass case and the containing space is kept cold either by artificial refrigeration or by ice, but the invention is particularly intended for use in connection with artificial refrigeration.

In the accompanying drawings, which illustrate the invention, like characters indicate like parts throughout the several views.

Referring to the drawings:

Fig. 1 is a perspective showing a refrigerator counter embodying my invention;

Fig. 2 is an enlarged transverse section on the line 2—2 of Fig. 1; and

Fig. 3 is an enlarged fragmentary view showing one of the hinges for connecting the control work board or leaves to the containing receptacle.

The body of the counter is an elongated rectangular structure, preferably a wooden box 4 supported on a suitable rectangular framework 5. A work board, preferably in the form of several leaves 6, is connected to the rear upper portion of the box 4 by double-jointed hinges 7 that permit said leaves to be turned upward, inward and then completely downward against the back or exterior of the innermost side of the box. Normally, however, the leaves 6 at their free ends rest upon vertical posts or brackets 8 rigidly secured to the bottom of the box. The box is provided with a heavy lining 9, of a good insulating material, such as chipped cork, which, in turn, is faced on its inner surface with a sheet metal lining 10. Here it will be noted that the flanged lower ends of the posts 8 are directly secured to the bottom of the box, being directly secured on the bottom of the lining 10. In the space underlying the work-board-forming leaves 6 and at the rear of the posts 8, there is a refrigerator-containing space 11. Preferably, a woven wire screen 12 is attached to the posts 8 and is extended longitudinally from end to end of the box and vertically from the top of the posts to a line considerably

above the lining plate 10. The foot-containing and displaying compartment 13 is forward of the posts 8 and screen 12 and is below the level of the work board or leaves 6, and this space is covered by a glass case 14 formed with oblique front and rear walls, the latter having suitable sliding doors 15.

Supported from but above the board of the compartment 13 is a rack 16, preferably in the form of a woven wire screen having supporting legs 17 and adapted to support a plurality of food-containing trays 16' or to directly support articles of food placed directly on the said screen. Here it will be noted that the rack 16 is spaced above the bottom of the compartment 13, so that cold air may freely circulate thereunder and upward through the rack-forming screen 16. Here a highly important feature should be noted, to wit: that the display-supporting rack 16 is located far below the level of the upper portion of the insulated or solid box body and far below all of the glass or transparent portion of the show case. This will support the meat or other perishable food where the cold circulating air will be forced all around the same. In practice, it has been found that the temperature of the air below a horizontal plane at the top of the insulated box is very much lower than the temperature of the air further upward or within the space enclosed by the glass. Otherwise stated, the goods displayed on the rack are not visible from a level below the top of the insulated box, but are set down into the box within the circulating currents of cold air and the warmer air will be pocketed within the upwardly projected transparent portion of the show case.

It is further important to note that the upper portion of the bottom of the entire box, or that portion afforded by the bottom lining 10, inclines forwardly from the bottom of the refrigerator-containing space 11 to the front of the display compartment 13 and from thence is rounded upward and slightly turned backward. This performs an important function which will be presently noted.

In some cases, ice may be placed in the refrigerator-containing space 11, but in the preferred arrangement, an artificial refrigerator, comprising a long cylinder 18 containing brine-circulating coils 19, is extended longitudinally through said space 11 but is spaced from the bottom, top and rear walls

thereof, being, as shown, thus supported by brackets 20. With the arrangement described, the air will, of course, be reduced in temperature by the refrigerator 18-19 and the coldest air will fall and, by the inclined bottom, will be directed forwardly under the rack 16 and, as the air is raised slightly in temperature, it will be drawn backward over or around the articles contained on the 10 rack and over the top of the cylinder 18, so that the circulation will be almost entirely as indicated by the arrows on Fig. 2, although there will be some circulation of cold air upward through the screen or perforated rack, which also facilitates the cooling action. The circulation under the vertical screen 12 will be preferably free, but the backward circulation toward the cylinder 18 will be split up and the returning air will 20 be directly against substantially the entire surface of said cylinder. The curved formation of the front portion of the lining 10 also assists somewhat in directing the returning air toward the articles contained on 25 the rack.

Here it should be further noted that the insulated front portion of the box extends upward to a horizontal line that is approximately tangential with the top of the cylinder 19, so that substantially all of the circulation of air in the cooling action will be 30 below the upper portion of the insulated walls of the box and there will be but very little circulation within the glass case 14 and, 35 hence, there will be but little waste of cold

temperature due to opening of the doors 15. In this way, a maximum of efficiency is obtained. The numeral 21 indicates a drain pipe extending downward from the front and lowest portion of the lining 10 to a suitable point of discharge. 40

In actual practice, this refrigerator counter has been found of extremely high efficiency and great convenience, as well as ornamental in appearance, and sanitary. 45

What I claim is:

A refrigerating display device for food products comprising a casing adapted to be placed upon a counter, said casing containing two compartments arranged side by side, one of which constitutes a food chamber and the other of which constitutes a refrigerating chamber, an inclined false bottom for said food chamber which has its highest end at the junction between said chambers and its lowest end adjacent the front wall of said casing, a member forming the outer longitudinal wall of said food chamber and which has an interior curved surface the upper portion of which is deflected inwardly toward the top of said food compartment and the lower portion of which is deflected inwardly so as to merge into the lower portion of said false bottom, and a receptacle supported in said food chamber, said receptacle being spaced above said false bottom and spaced inwardly from said curved surface. 55 60 65

In testimony whereof I affix my signature.

EDWARD J. LA FONTAINE.
